HENRY B. COOLEY, OF NEW BRITAIN, CONNECTICUT, ASSIGNOR TO THE AMERICAN PAPER GOODS COMPANY, OF KENSINGTON, CONNECTICUT, A CORPORATION OF NEW JERSEY.

FEEDING AND CREEASING DEVICE.

1,107,194.

Specification of Letters Patent. Patented Aug. 11, 1914.

Application filed June 18, 1913. Serial No. 774,340.

To all whom it may concern:

Be it known that I, HENRY B. COOLEY, a citizen of the United States, and a resident of New Britain, in the county of Hartford and State of Connecticut, have invented a new and Improved Feeding and Creasing Device, of which the following is a specification.

My invention pertains more especially to machines for folding paper or like material and such as are commonly employed in connection with envelop folding machines, and an object of my invention, among others, is to provide a device of this class that shall 15 be adapted to operate upon envelops or like articles of various sizes.

One form of device embodying my invention and in the construction and use of which the objects herein set out, as well as 20 others, may be attained is illustrated in the accompanying drawings, in which—

Figure 1 is a view in front elevation of some of the rolls of an envelop folding machine showing my invention applied thereto. 25 Fig. 2 is a view in cross section through the frame of the machine on plane passing through the axis of the creasing rolls. Fig. 3 is a view in vertical cross section through the creasing rolls. Fig. 4 is a detail view 30 showing the creasing rolls in position to grasp a blank.

In the accompanying drawings the creasing rolls include one member having a creasing groove to receive a creasing rib from the 35 other roll, the numeral 5 denoting the shaft of the creasing bar roll and 6 the shaft of the grooved creasing roll, which rolls travel in coöperative relation, said shafts being suitably mounted in bearings of any ordinary 40 construction upon the frame of the machine. These shafts have intermeshing gears 7—8 secured thereto and driven in any suitable manner, as herein shown a gear 9 meshing with the gear 7 supplying the 45 driving power.

The grooved creasing roll 10 is mounted upon the shaft 6 and has a groove 11 formed in its periphery extending lengthwise of the roll. This roll is mounted for adjustment 50 upon the shaft in a circumferential direction, screws 12 affording a means for securing the roll to the shaft after proper adjustments have been obtained.

The other creasing roll is composed of a 55 feed roll 13 and creasing bar rolls 17 ro-

tatably, adjustably mounted upon the shaft 5. Screws 14 may be employed for securing the feed roll to the shaft, and screws 18 for securing the creasing bar rolls to the shaft. The feed roll is cut away, as at 15, 60 for a portion of the distance about its periphery, the advance edge 16 of the full portion of the roll forming a "grab" between which and the roll 10 the envelops or like articles are grasped and moved along. In 65 securing the feed roll and creasing bar rolls to the shaft split bushings 19 are located between the rolls and shaft 5, and the screws 14 and 18 impinge upon these bushings. A groove 20 is formed in the fullest portion of 70 the feed roll 13.

Recesses 21 are formed in each of the creasing bar rolls 17, in which recesses a creasing bar 22 is secured, extending from one of the creasing bar rolls to the other 75 across the cut away part 15 of the feed roll. This creasing bar is secured in any desired manner, and it has a rib 23 formed to enter the groove 11 for the purpose of forming a crease in an envelop or like article passing 80 between the rolls.

Different sizes and varieties of envelops or like articles cause the crease or creases to be located in different positions with respect to the advance edge of the envelop, 85 and in order to enable these creases to be located in proper position on the envelop it is necessary that the creasing devices may be located in different positions, and in locating these devices in different positions it, 90 of course, is essential that the roll bearing the crease shall register with that bearing the creasing bar. In order to simplify the adjustment of the parts in arranging the creasing devices for any special work I employ sleeves 24—25 mounted on the shafts 5—6 respectively, these sleeves being secured to the rolls as by means of screws passing through flanges 26. Each of these sleeves have intermeshing gears 27 secured thereto, 100 which gears are of such size and have the teeth so formed thereon that they will freely intermesh when the two rolls are rotated in unison as compelled by the gears 7 and 8.

The rolls above described are mounted in 105 side parts 28 of the machine and supply rolls 29—30 may be employed to deliver the envelops to the creasing rolls, and rolls 31 to take the envelops away from the creasing rolls. Any suitable means for supplying 110

the creasing rolls may, however, be employed, and my invention is not therefore necessarily restricted to any particular means for feeding the envelopes. When 5 such supply rolls are employed the periphery of one of them will be cut away, the roll 30 being shown herein as so cut away at 32 and the supply rolls, or other means that may be employed to deliver the envelopes to the creasing roll will be so arranged and operated that the envelopes will be delivered to the creasing rolls in a predetermined position with respect to the "grab" 10 on the creasing members. The cut away part 32 is provided for the purpose of enabling the rolls to instantly and surely 15 grasp the envelopes, and thus insure uniformity of feed and avoid any slipping back of the paper in the wedging action of the rolls and before the edge of the blank is grasped by the rolls, and the distance from the advance edge of the uncut away part of the roll 32 to the rear edge thereof will be sufficient to feed the envelopes into the 20 space between the cut away portion 15 of the feed roll 13 and the creasing roll 10, which latter rolls will be in this relative position at the time the envelop is presented to them. The rotation of the several rolls 25 will be properly timed with respect to one another to present the advance edge of the envelopes into this space between the creasing rolls just before such space is closed, and the distance from the "grab" 16 backwardly to the rib 23 will be substantially 30 the distance from the advance edge 33 of the envelop to the line 34 to be creased, when the advance edge 33 is presented between the rolls substantially coincident with the 35 "grab" 16. The position of the envelop is shown in dotted lines in Fig. 1, this style of envelop being subsequently creased on the dotted lines 35, from which it will be seen that the flaps 36 travel on the creasing bar 40 rolls 17, the advance edge 33 of the envelop 45 determining its proper position with respect to the rolls.

It is essential that the groove 11 and the 50 rib 23 shall always be so relatively located that the rib will enter the groove in the rotation of the rolls. It becomes essential to frequently change the location of the creasing bar and the rib 23 thereon, by reason of operations upon different sizes of envelopes, 55 and the construction preserves the proper relative arrangement of the groove and rib at all times during such adjustments.

While I have shown and described herein 60 a satisfactory arrangement of parts for accomplishing the desired result, this may be departed from to a greater or lesser degree and yet be within the spirit and intent of the invention.

I claim:

65 1. A pair of creasing rolls, one of said

rolls having a groove and the other including a shaft, a feed roll secured to the shaft and having a cut away portion forming an advance edge to grasp a sheet, creasing bar rolls secured to the shaft at opposite ends 70 of the feed roll, and a creasing bar secured to the creasing bar rolls and extending across the cut away portion in the feed roll and having a rib to mate with the groove in the opposite roll. 75

2. A pair of creasing rolls, one of which has a groove and the other of which includes a shaft with creasing bar rolls secured thereon, a feed roll mounted between the creasing bar rolls and movable independently thereof 80 for adjustment purposes and cut away on one side for a portion of the distance around its periphery, and a creasing bar secured to said creasing bar rolls and extending across said cut away portion of the feed roll and 85 having a rib arranged to mesh with said groove.

3. A pair of creasing rolls, one having a groove and the other including a shaft with a feed roll mounted thereon and having a 90 portion cut away on one side lengthwise thereof, means for adjustably positioning the feed roll in a circumferential direction on the shaft, a pair of creasing bar rolls mounted on the shaft at each end of the feed 95 roll, means for adjustably positioning the creasing bar rolls independently of the feed roll, and a creasing bar secured to the creasing bar rolls and extending across the cut away portion of said feed roll. 100

4. A pair of creasing rolls, one of which includes a shaft and a roll having a groove extending lengthwise thereof, means for adjustably positioning said roll and securing it to the shaft, a second roll including a shaft, 105 a feed roll mounted on the shaft and having a cut away portion, creasing bar rolls mounted on the shaft, means for adjustably positioning the creasing bar rolls and securing them to the shaft, a creasing bar secured to the creasing bar rolls and having a rib to mate with the groove in the opposite roll, intermeshing members between the grooved roll and the creasing bar rolls to compel simultaneous movement for adjustment purposes, and means for driving said rolls. 110

5. A pair of creasing rolls one of which includes a shaft and a roll mounted thereon and having a creasing groove, means for 120 adjustably positioning said roll for securing it to its shaft, a second shaft, intermeshing gears secured to said shafts, a feed roll mounted on the second shaft, means for adjustably positioning the feed roll and for 125 securing it to its shaft, a pair of creasing bar rolls mounted on the shaft at opposite ends of the feed roll, means for adjustably positioning the creasing bar rolls and for securing them to their shafts, a creasing bar 130

secured to said creasing bar rolls, and intermeshing gears secured to the creasing bar roll and to the mating grooved roll.

6. A pair of creasing rolls, one of said rolls having a groove and the other including a shaft, feeding means mounted on the shaft and having a cut-away portion forming an advance edge to grasp a sheet, means upon said shaft to support a creasing bar at

opposite ends thereof, and a creasing bar 10 secured to said creasing bar support and extending across said cut-away portion and having a rib to mate with the groove in the opposite roll.

HENRY B. COOLEY.
